(57) **CLAIM**

The ornamental design for a display screen with graphical user interface for player tracking in a sporting event, as shown and described.

DESCRIPTION

FIG. 1 is a front view of a display screen with graphical user interface for player tracking in a sporting event, showing the novel design; and,

FIG. 2 is a front view of a display screen with graphical user interface for player tracking in a sporting event, showing a second embodiment of the novel design.

The outermost broken line perimeter showing the display screen and the broken lines therein showing features of the graphical user interface are provided for the purposes of illustrating portions of the article and form no part of the claimed design.

1 Claim, 2 Drawing Sheets
